UNITED STATES PATENT OFFICE.

WILLIAM C. SANCTUARY AND WENDELL A. JONES, OF AMHERST, MASSACHUSETTS.

BROODER.

Original application filed June 14, 1924, Serial No. 720,010. Divided and this application filed October 26, 1925. Serial No. 64,859.

Our invention relates to improvements in brooders, and it consists in the combinations, constructions and arrangements herein described and claimed.

5 This application is a divisional part of our prior application, Serial #720,010, filed June 14, 1924.

An object of the invention is to provide a brooder which affords facilities for maintaining the correct temperature for chicks over a relatively great area and for producing a temperature gradient which increases gradually and regularly from the outer edge of the hover of the brooder to a central 15 source of heat.

A further object of the invention is to provide a brooder which has means for protecting the chicks which are sheltered thereby from incoming currents of cold air.

20 A still further object of the invention is to effect an economy in the use of fuel for heating to a satisfactory temperature a given space.

Other objects and advantages will be apparent from the following description, considered in conjunction with the accompanying drawings, in which

Figure 1 is a vertical section through the improved brooder and through a portion of 30 the supporting floor,

Figure 2 is a horizontal section through the heating unit of the brooder, the view being taken substantially along the line 2-2 of Figure 1.

35 Figure 3 is a relatively enlarged fragmentary perspective view of cooperating portions of the heater casing and a rotary valve or shutter for controlling flow of air through lateral ports in the heater casing.

40 The improved brooder includes a heater unit indicated generally at 1 which comprises a casing or hollow body 2 in which coal or like fuel may be burned. The gases and waste products of combustion may pass 45 from the casing 2 through a flue pipe 3 which may extend from the top of the casing 2 to any desirable place. The heater casing 2 is supported on a cylindrical base 4 which may rest upon a supporting floor 5 or platform 5 over an opening 6 in said 50 floor or platform.

The cylindrical base section of the heater casing has a draft opening 7 adjacent to the upper end thereof through which air 55 may pass into the heater casing for sup-

porting combustion therein. The cylindrical base section 4 also has a circumferentially extending series of spaced openings 8 in the lower end portion thereof. A rotary annular shutter plate or valve 9 fits 60 within the lower end portion of the base section 4 and has circumferentially spaced openings 10, corresponding in number, area, and relative arrangement with the openings 8, whereby corresponding openings 8 and 10 65 will be in register when the rotary shutter 9 is in a certain position. A stud 11 that is carried by the shutter plate 9 extends slidably through a slot 12 in the lower end portion of the base section 4. This stud 11 has 70 a head at its outer end which can be conveniently manipulated by the finger of an operator and the shutter plate thus rotated within limits to move the respective openings 10 of the shutter plate partially or 75 completely out of register with the corresponding openings 8, whereby the volume of air that is permitted to pass from the space within the base section 4 of the heater casing to the space which surrounds the lower 80 end portion of the base section 4 of the heater casing can be regulated and passage of air from the space within the base section 4 of the heater casing through the openings 8 to the space which surrounds 85 the lower end portion of the base section 4 of the heater casing can be prevented when desired.

The opening 6 in the floor 5 permits the passage of air into the space within the base section 4 of the heater casing. An annular baffle 13 surrounds the heater casing in adjacent but spaced relation to the heater casing, the baffle 13 resting at its lower end on the floor 5 and extending well above the 90 level of the draft opening 7.

A damper or draft check 14 for the heating unit may be operated by a rod 15. The rod 15 is supported on a frame 16 so that it can move axially to open or close the draft 100 or check 14 and the axial movement of this rod 15 is controlled by a thermostatic element 17.

A hover comprises a frusto-conical body 18 which is supported at its upper end on 105 the upper end portion of the heater casing 2 and terminates at its lower and larger end above the level of the floor 5. A skirt 19 depends from the lower edge of the hover 18 nearly to the floor or platform. The 110

skirt 19 is made of a suitable flexible material, such as a heavy fabric.

From the foregoing description of the various parts of the device, the operation thereof will be readily understood. With the construction shown, the temperature gradient will show a gradual and regular increase from the outer edge of the hover plate to the central source of heat, thus increasing the area of correct temperature for chicks, commonly termed the "chick circle area". Air passing through the openings 6 into the hollow base section of the heater casing and then through the openings 10-8 will be deflected upwardly by the baffle 13 close to the heater body and will be warmed before passing from the upper end of the baffle 13 into the space under the hover. The temperature beneath the hover 18 will be regulated automatically by means of the thermostat 17. The chicks beneath the hover plate thus will be protected from drafts of cool air because of the outward direction of the warmed air, particularly at and near the edge of the hover plate and the temperature beneath the hover plate will increase gradually and regularly from the outer edge of the hover plate toward the heater drum. As a result, the capacity of a brooder of a given size is increased beyond the ordinary when a brooder embodying the invention as hereinbefore described is used and the brooder may be located in a cooler room than is usual, which is a very desirable feature for the growth of vigorous, hardy chicks.

Obviously, the invention is susceptible of embodiment in forms other than that which is illustrated in the accompanying drawing and we therefore consider as our own all such modifications and adaptations thereof as fairly fall within the scope of the appended claims.

We claim:

1. A brooder comprising a heater casing, said casing including a cylindrical base section adapted to rest on a horizontal supporting member over an opening in said horizontal supporting member, said cylindrical base section having a circumferentially spaced

series of openings in the lower end portion thereof, a rotary annular shutter plate for controlling said openings in said base section, said shutter plate having openings corresponding in number and relative arrangement with the openings in said base section, and an annular baffle encircling the lower end portion of said heater casing and resting upon said supporting member, said annular baffle extending close to said heater casing above the level of said openings in the base section of the heater casing.

2. A brooder comprising a heater casing, said casing including a cylindrical base section adapted to rest on a horizontal supporting member over an opening in said horizontal supporting member, said cylindrical base section having a circumferentially spaced series of openings in the lower end portion thereof, a rotary annular shutter plate for controlling said openings in said base section, said shutter plate having openings corresponding in number and relative arrangement with the openings in said base section, and an annular baffle surrounding the lower end portion of said heater casing and resting upon said supporting member, said annular baffle extending close to said heater casing above the level of said openings in the base section of the heater casing, and a substantially frusto-conical hover carried by the upper end portion of said heater casing and depending below the level of the upper end of said annular baffle.

3. In a brooder, a heater casing cylindrical as to its base and perforated therein and flared in its upper portion, an annular baffle surrounding said heater casing parallel thereto and uniformly spaced therefrom as to the casing's cylindrical and flared portions, means for admitting intake air to the space between said baffle and said heater casing and a frusto conical hover plate surrounding the said heater casing and supported at its upper end from the heater casing above the upper end of the annular baffle so as to be held off the ground.
